Patented July 23, 1918.

FIG. 1

FIG. 2

FIG. 4

Bryson Dexter Horton
and Frederick Zenker, Inventors
By their Attorney

Clifford E. Dunn

UNITED STATES PATENT OFFICE.

BRYSON DEXTER HORTON, OF DETROIT, AND FREDERICK ZENKER, OF HIGHLAND PARK,
MICHIGAN, ASSIGNEES TO DETROIT FUSE & MFG. COMPANY, OF DETROIT, MICHIGAN,
A CORPORATION OF MICHIGAN.

CONNECTOR.

1,273,225.

Specification of Letters Patent. Patented July 23, 1913.

Application filed July 14, 1913. Serial No. 109,230.

To all whom it may concern:

Be it known that we, BRYSON DEXTER HORTON, a citizen of the United States, residing at Detroit, county of Wayne, and State of Michigan, and FREDERICK ZENKER, a subject of the Emperor of Germany, residing at Highland Park, county of Wayne, and State of Michigan, have invented certain new and useful Improvements in Connectors, of which the following, taken in connection with the accompanying drawings, is a full, clear, and concise description thereof.

Our present invention relates more particularly to certain new and improved connecting means and particularly to means for connecting switch contacts of the knife-blade type, so as to operate in unison and be in perfect alinement with respect to the co-operating contacts.

Our invention further relates to simplified means for connecting the switch-blade connecting means with an operating crank or member, all of which will be more fully described in detail in the following specification, reference being had to the accompanying drawings in which we illustrate by way of example certain preferable structural embodiments of the features constituting our invention.

Figure 1 is a view in perspective of a two-pole switch embodying a preferred form of our invention.

Fig. 2 is a fragmentary enlarged detail of the preferred embodiment of our invention shown in Fig. 1.

Fig. 3 is a view in perspective of the blank from which is formed the connecting device employed for joining the cross-head of the knife-blade contacts illustrated in Figs. 1 and 2. Fig. 4 is a view similar to Fig. 2 showing a modified form of connecting means for joining the knife-blade contacts.

In the general class of electrical switches, to which our invention is especially applicable, a plurality of knife-blade contacts 1 are pivotally mounted at one end, as at 2, to suitable supports 3, which are in electrical connection with the binding posts 4. The free ends of these knife-blade contacts are co-operatively associated with a pair of spaced jar contacts 5, which are in electrical connection with the binding posts 6, when fuses are positioned within the fuse

holders 7. The knife-blade contacts 1 are connected with a member referred to as a cross-head, through which the power is applied to operate the movable knife-blade contacts in unison. In the switch illustrated in Fig. 1, the cross-head is indicated by the numeral 8 and this is shown cooperatively associated with an operating crank member 9 which is suitably journaled in the side of the protective casing or housing. The crank 9 is preferably formed of one piece and is provided with an exterior arm portion, by means of which the switch may be operated.

As stated, our invention particularly has to do with the manner of cross-connecting the knife-blade contacts and the manner in which the cross-connecting means is operably connected with the operating crank or handle. In the preferable embodiment of our invention we form the cross-head 8 of insulating material of rectangular cross-section, as such form serves best to accommodate the connecting devices, which connect the same with the knife-blade contacts. These connecting devices are of like construction and a description of one will therefore suffice. The connecting device is formed of a single piece of sheet metal in the shape of a cross, as shown in Fig. 3. The cross-head is provided with a slot or aperture 10 through which the long end of the device 11 is projected, this end being bent over beneath the cross-head 8 as at 12. Further bends to the long arm 11 are then given, so as to extend a portion along the top of the cross-head as at 13, and then at right-angles thereto as at 14 at the end of the cross-head. Short arms 15 of the connector are bent at right angles to the portion 14, these short arms being projected through suitable openings in the knife-blade contacts. When this is done, the extremities are given a right-angle bend, so that both will lie against the outer surface of the knife-blade as at 16. Thus, it will be seen, that both the knife-blade and the cross-head have portions thereof inclosed within rectangular openings formed by bending the connecting member in the manner illustrated. This provides a very substantial connecting medium and one which can be made at very little expense. It will be observed, moreover, that the cross-head and

connecting members are positioned below the upper edges of the knife-blades and extend completely across between them so as to keep the same in perfect alinement, and in a manner whereby they will be operated in unison.

In the modification shown in Fig. 3, we use a cross-connecting member 17 of cylindrical formation, the same comprising preferably a tubular insulating sleeve into the ends of which metallic plugs 18 are inserted, these metallic plugs being riveted to the knife-blade contacts by rivets 19 and fastened to the insulating sleeve by the rivets 20. This form of construction possesses certain of the advantages of the preferred form described.

In order to provide for a balanced pull on the knife-blade contacts when manipulating the same, a connecting member is provided, the same being located intermediate of the knife-blade contacts and having an eye which coöperates with the end of the operating crank 9. The particular means employed for this purpose constitutes one of the important features of our invention. In the preferred embodiment shown in Fig. 2, this connecting member takes the form of an eyelet made of half round cotter pin stock, and is shown with an eye 21 through which the end of the operating crank 9 projects. The ends of the member are inserted through an opening in the cross-head with suitable washers 22 and 23 disposed upon both upper and lower sides of the cross-head. The extremities of the members are thereafter bent over in opposite directions, so as to securely connect with the cross-head. In Fig. 4, we illustrate a simple form of eye-bolt which extends through the tubular cross-head, the extremities of the bolt being provided with a binding nut 24, which maintains it in proper relation to the cross-head. Suitable curved washers 25 and 26 are used to provide a firm connection.

While we have illustrated in the accompanying drawings certain preferred constructions involving the features of our invention, we do this by way of example only and we do not wish to be limited to the exact details as changes may be resorted to without departing from the spirit and scope of our invention as defined by the following claims.

Having thus described our invention, what we claim as new herein and desire to secure by Letters Patent is:—

1. A connector embracing a cross head located between the members to be connected, and connecting devices each interlocking with said cross head and one of the members to be connected to lock them to said cross head.

2. A connector embracing means cross connecting members to be connected so as to

maintain them in alinement and move them in unison, said connecting means including a member formed of insulating material, and connecting devices each interlocking with one of the extremities of said insulating member and one of the members to be connected.

3. Connecting devices comprising an insulating member of rectangular cross section positioned between the members to be connected and within the rectangular outline thereof, and metal connecting devices each interlocking with one of the extremities of the insulating member and one of the members to be connected.

4. A connecting device comprising an insulating member extending across and between the members to be connected and connecting devices for independently connecting the insulating member to the members, each device being formed of a single piece of sheet metal and having a portion extending through the member and bent over to extend in a plane common thereto, and portions extending through the adjacent member to be connected and bent over in a plane common to the latter.

5. A connecting device comprising a cross head of insulating material and metal connectors connecting the same to members to be connected, said metal connectors being provided with portions which surround portions of both the insulating member and the members to independently connect them to said insulating member.

6. A connecting device embracing a cross-head and connectors each comprising a cross-shaped member with certain of its arms interlocking with said cross-head and other of its arms interlocking with members to be connected to independently lock them to said cross-head.

7. A connecting device embracing a cross-head of insulating material, and metal connectors each comprising a cross-shaped member with certain of its arms interlocking with said cross-head and other of its arms interlocking with the members to be connected to independently lock them to said cross-head.

8. A connecting device embracing a cross-head, and connectors each comprising a sheet metal cross-shaped member with certain of its arms interlocking with said cross-head and other of its arms interlocking with the members to be connected to independently lock them to said cross-head.

9. A connecting device for slotted members embracing a slotted cross-head, and connectors each comprising a sheet metal cross-shaped member with certain of its arms coöperating with the slots of said members to be connected and bent relative thereto, and other of its arms coöperating with the slots of said cross-head and bent relative thereto.

to independently lock said members to be connected to said cross-head.

10. A connecting device for slotted members to be connected embracing a slotted cross-head and connectors each comprising a sheet metal cross-shaped member with two of its arms extending through the slot in a

member to be connected and bent relative thereto and another of its arms extending through a slot in said cross-head and bent 10 relative thereto to independently lock said members to be connected to said cross-head.

BRYSON, DEXTER HORTON,
FREDERICK ZENKER:
